SIDE WALL SAMPLE TAKER

Maurice Mennecier, Houston, Tex., assignor to
 Schlumberger Well Surveying Corporation,
 Houston, Tex., a corporation of Delaware

Application May 15, 1946, Serial No. 669,923

10 Claims. (Cl. 255—1.4)

1

The present invention relates to side wall sample takers for use in bore holes drilled into the earth. More specifically, it relates to a new and improved side wall sample taker which greatly facilitates the taking of cores from harder formations such as limestone, for example, although it is not limited to such use.

It has been proposed, heretofore, to employ apparatus comprising a motor driven drill bit, under pressure, for taking samples from the harder formations traversed by a bore hole. In some designs, hydraulic means, powered by the motor, has been used for applying pressure to the drill bit and also for actuating means to anchor the apparatus at a desired location in a bore hole.

In general, such apparatus is not entirely satisfactory for commercial operations, because the occurrence of a power or motor failure after the apparatus has been anchored in drilling position makes it impossible to withdraw the apparatus from the well. Also, the drill pressure in such apparatus varies with the drilling rate so that optimum drilling conditions for the various types of formations encountered cannot be maintained without modifying the apparatus. Moreover, such apparatus in which the motor is reversed to withdraw the sample from a formation is not always effective, but may leave all or part of the sample in the formation, especially where the latter is quite hard.

The principal object of the present invention, accordingly, is to provide new and improved side wall sample taking apparatus which is free from the above noted deficiencies of the prior art and which is simple and reliable in operation.

Another object of the invention is to provide new and improved side wall sample taking apparatus of the above character which can be readily withdrawn from a bore hole if the power or driving means fails after the apparatus is anchored in operating position in the bore hole.

A further object of the invention is to provide new and improved side wall sample taking apparatus of the above character in which the pressure on the drill is maintained substantially constant, regardless of the cutting rate of the drill.

Still another object of the invention is to provide new and improved side wall sampling apparatus of the above character which includes novel means for breaking the core substantially at the maximum depth of penetration of the drill.

2

A still further object of the invention is to provide new and improved side wall sampling apparatus of the above character which can be completely reset in the bore hole after a sample has been taken, so that the apparatus can be removed to another depth and an additional core or cores can be taken.

The objects of the invention are attained by providing guiding means in the body of a side wall sample taker, in which drilling and sample receiving means is slidably mounted for movement toward and away from the side wall of a bore hole. The drilling and sample receiving means is adapted to be operated by electrical motive means which is slidably mounted in the body of the sample taken in such fashion that the weight of the motive means is applied to the drilling and sample receiving means during the sample taking operation. Also, means are provided for automatically applying a force to the drilling and sample receiving means, after the latter has penetrated a predetermined distance into a formation, to break off the sample that has been cut so that it can be recovered.

The cable on which the sample taker is lowered into a bore hole is secured to the electrical motive means, so that, once the sample taker has been anchored at a given depth in a bore hole, lowering the cable permits the weight of the electrical motive means to be applied to the drilling and sample receiving means, while raising it withdraws the drilling and sample receiving means from the side wall of the bore hole.

The sample taker according to the present invention is adapted to be anchored in operating position by laterally movable wall gripping means, which preferably cooperates with wall gripping means on the body of the sample taker to effect this result. The cooperating wall gripping means are rendered effective by the weight of the body of the sample taker so that the latter may be readily dislodged merely by pulling it upwardly in the bore hole. The laterally movable wall gripping means is normally retained within the body of the sample taker but is adapted to be released by the operation of the electrical motive means which operates the drilling and sample receiving means.

Means are also provided whereby the laterally movable wall gripping means may be moved into inoperative position within the body of the sample taker, and the drilling and sample receiving means may be reset and restored to the initial

position merely by pulling up the supporting cable and raising the electrical motive means while the body of the sample taker is in the bore hole.

It will be apparent, therefore, that a sample taker constructed according to the present invention can be readily withdrawn from a bore hole even if a power or motive means failure occurs during the sample taking operation. Moreover, since the weight of the motive means is applied to the drilling and sample receiving means, the latter operates under constant pressure, regardless of the rate at which it cuts into the formation, and this constant pressure can be adjusted for optimum drilling conditions by controlling the weight of the motive means. This is an important factor, since operation of many hard formation drills such as diamond drills, for example, is much improved if an optimum value of drill pressure is maintained.

The invention may be better understood from the following detailed description of a representative embodiment, taken in conjunction with the accompanying drawings, in which:

Figure 1 is a partial view in section taken along line 1—1 of Figure 4, looking in the direction of the arrows, and showing the upper portion of a side wall sample taker constructed according to the present invention;

Figure 2 is a partial view in section taken along line 1—1 of Figure 4, looking in the direction of the arrows, and showing the lower portion of the side wall sample taker illustrated in Figure 1;

Figure 3 is a detailed view showing the retainer rod for the movable side wall gripping means in a position rotated substantially 90° counterclockwise from the position shown in Figure 1, and illustrating the opposite flats thereon;

Figure 4 is a view in transverse section taken along the line 4—4 of Figure 1, looking in the direction of the arrows, and illustrating the manner in which the cam for releasing the movable wall gripping means is actuated;

Figure 5 is a partial detailed view taken along line 5—5 of Figure 2, and showing means for resetting the mechanism for breaking off a sample to its initial position;

Figure 6 is a view in longitudinal section showing a side wall sample taker constructed according to the invention with the movable side wall gripping means in the operative position, but before the drilling and sample receiving means has penetrated a formation; and

Figure 7 is a view in longitudinal section illustrating the manner in which a sample cut from a formation is broken off.

Referring now to Figures 1 and 2, a side wall sample taker is shown comprising an elongated body 10 having an upper cylindrical portion 11, and a lower support member 12 terminating in a bullet shaped bottom member 13. The upper cylindrical portion 11 of the body 10 has formed therein a chamber 14 which is closed off at its lower end by a transverse partition 15 and which communicates at its upper end with a bore 16 of reduced diameter. Within the chamber 14 is disposed a cylindrical water-tight housing 17 containing a conventional type motor 18 which may be energized and controlled in any suitable manner as by a source of electrical energy B, switch S and ammeter M, at the surface of the earth, connected to the conductors C in the cable 30. Above the housing 17 is disposed a head 29 which is adapted to be slidably received

within the bore 16, and to which a supporting cable 30 is secured in the usual manner.

The mechanical output of the motor 18 is transmitted from the shaft 19 and through the speed reduction gearing 20 to a shaft 21 which extends through a transverse partition 22 forming a lower water-tight closure member for the housing 17. Any suitable gear reduction ratio may be used, but a ratio of five to one has been found satisfactory where the motor 18 operates at 3600 R. P. M.

Leakage of bore hole fluid about the shaft 21 into the housing 17 is prevented by a suitable packing gland 23. In order to permit the use of a packing gland 23 which will not impose an excessive load on the motor 18, and still prevent the entry of bore hole fluid into the housing 17 at the extremely high fluid pressures ordinarily encountered in a bore hole, it is desirable to provide suitable means for equalizing the pressures inside and outside the housing 17. Such pressure equalizing means may comprise, for example, conventional type Sylphon bellows 24, tightly secured above the housing 17 in a chamber 29' formed in the head 29. The interior of the bellows 24 communicates with the interior of the housing 17 through the passages 25 formed in the top wall of the housing 17. Communication is also provided between the motor 18 and the reduction gearing 20 through the passages 26 formed in a transverse partition 27 disposed between the motor 18 and the gearing 20. The Sylphon bellows 24 and the space surrounding the motor 18, and the gearing 20, are filled with a suitable fluid such as oil, for example, and the bore hole fluid is permitted access to the outside of the Sylphon bellows 24 through a plurality of apertures 28 formed in the head 29, so that the pressures inside and outside the housing 17 are effectively equalized.

The housing 17 is slidably mounted within the chamber 14 and a plurality of longitudinally extending guide slots 30 are provided in the upper cylindrical portion 11 of the body 10, within which a plurality of guide pins 31 mounted on the housing 17 are adapted to be slidably received.

The mechanical output from the shaft 21 is transmitted through a conventional flexible cable 32, which passes through the transverse member 15 and through a rigid supporting tube 33 shaped as shown in Figure 2, and which is secured to the rear wall of the drilling and sample receiving means 34. The drilling and sample receiving means 34 may comprise a conventional hollow diamond drill having a bit 35 at the forward end thereof of greater diameter than the drilling and sample receiving means 34. Suitable means are provided for retaining the core within the drilling and sample receiving means 34, such as for example, a plurality of inwardly bent spring fingers 36 mounted in any suitable manner in the longitudinal slots 37.

The drilling and sample receiving means 34 is slidably mounted within a bore 38 formed in a heavy block 39 which is mounted on supporting pins 40 secured to the lower support member 12 of the body 10, which extend through slots 41 formed in the block 39. It will be seen that this construction permits restricted movement of the block 39 substantially perpendicularly to the direction of travel of the drilling and sample receiving means 34.

The block 39 is normally securely held in the position shown in Figure 2, with the pins 40 in

the lowermost portion of the slots 41, by a stiff leaf spring 48, which is secured to the support member 12 at 49, and which cooperates with latching means 42 engaging a cam surface 43 on the block 39. The latching means 42 is pivoted on the support member 12 and 44 and is normally urged into engagement with the cam 43 by means of a compression spring 45, which is interposed between an arm 46 on the latching means 42, and a recess 47 formed in the upper face of the bullet shaped, bottom member 13.

The side wall sample taker of the present invention is adapted to be anchored at any desired level in a bore hole by means of side wall gripping means 50 which is movable laterally about a pivot 51 on the support member 12, and which is provided with a plurality of teeth 52 which are adapted to engage the side wall of a bore hole. The wall gripping means 50 cooperates with a plurality of wall gripping teeth 50', formed on the side of the body 10 opposite the wall gripping means 50, thus forming a toggle mechanism on which the weight of the body 10 acts, when the supporting cable 30 is lowered, to anchor the body 10 at a desired depth in a bore hole.

On the wall gripping means 50 is an arm 53 secured at the point 54 to a bar, which is connected by a conventional universal coupling 56 (Figure 1) to a retainer rod 57, which extends through a hub 58 formed on the transverse partition 15. The retainer rod 57 terminates in a head portion 59 below which are formed opposite flats 60 (Figure 3), which cooperate with a pair of downwardly extending spring detents 61 secured to the transverse partition 22 to retract the side wall gripping means 50 into the body 10 of the side wall sample taker in a manner to be described hereinafter.

The retainer rod 57 is maintained in the position shown in Figures 1 and 2 by means of a laterally projecting key 62 which rests on the upper edge of the hub 58, as shown in Figure 1, and which is maintained out of alignment with a longitudinally extending slot 63 in the hub 58 by means of a torsion spring 64, one end of which is secured to the retainer rod 57 and the other end of which is secured to the hub 58.

The side wall gripping means 50 is adapted to be released by means of a cam 65 mounted on the retainer rod 57, which is adapted to be actuated by a corresponding cam 66 mounted on the power shaft 21. As shown in greater detail in Figure 4, clockwise rotation of the shaft 21 causes the cam 66 thereon to engage the cam 65 on the retainer rod 57 and move the latter through substantially 90° counterclockwise, thereby bringing the key 62 (Figure 1) on the retainer rod 57 into alignment with the slot 63 in the hub 58. When this position is reached, the retainer rod 57 is drawn downwardly by means of a tension spring 67 (Figure 2), one end of which is secured to the bar 55 and the other end of which is secured to an eyelet 68 mounted on the support member 12. Downward movement of the bar 55 causes the wall engaging means 50 to pivot about the point 51 and to move laterally into engagement with the side wall of a bore hole.

Resetting of the drilling and sample receiving means 34, after the taking of a sample, may be accomplished by means of a rod 69, one end of which is secured within the transverse partition 22 (Figure 1) and the other end of which terminates in a head 71 of greater diameter. The rod 69 extends between the fork-like members 72

and 73 (Figure 5) of a laterally extending lug 70, which is secured to the block 39 and which is adapted to be lifted by the rod 69 when the cable 30 is raised. The lifting of the block 39 by the lug 70 in this manner permits the latch 42 to move into engagement with the cam 43 under the influence of the compression spring 45.

In operation, the side wall sample taker of the invention is inserted in a bore hole with the side wall gripping means 50 in the normally inoperative position inside the body 10, and with the other parts in the relative positions shown in Figures 1 and 2. In this fashion, it is lowered into a bore hole 74 (Figure 6) until the lower end of the drilling and sample receiving means 34 is at the level of a formation 75 from which it is desired to obtain a sample. Arrival at this level may be determined in any suitable manner, as by the method disclosed in prior Reissue Patent No. 20,120 to Conrad Schlumberger, in which an electrical prospecting device is lowered into a bore hole with a sample taker, to enable the latter to be brought to the level of a formation of interest. With the apparatus at rest in this position, the switch S (Figure 1) is closed and electrical energy is supplied to the motor 18 through conductors C in the supporting cable 30, causing the shaft 21 to rotate. As the shaft 21 turns, the cam 66 thereon moves the cam 65 on the retainer rod 57 so that the key 62 thereon is brought into alignment with the slot 63 in the hub 58 (Figures 1 and 4). The spring 67 then pulls the retainer rod 57 downwardly, permitting the side wall gripping means 50 to pivot about the point 51 and move laterally into engagement with the side wall of the bore hole 74, as shown in Figure 6.

The cable 30 is then lowered, permitting the weight of the body 10 to force the teeth 52 on the side wall gripping means 50 and the cooperating teeth 50' on the body 10 into the side wall of the bore hole 74, thus anchoring the body 10 securely in the bore hole 74. Lowering of the cable 30 also permits the weight of the motor 18 and the housing 17 to be transmitted through the flexible cable 32 to the drilling and sample receiving means 34, which meanwhile is being rotated by the motor 18. During the drilling operation, the load on the motor 18 is increased so that a rise in the reading of the ammeter M is noted, providing an indication of this operation at the surface of the earth. Rotation and advancement of the drilling and sample receiving means 34 continues until the latter has penetrated to the desired depth within the formation 75, as shown in Figure 7.

The depth of penetration of the drilling and sample receiving means 34 may be controlled by adjusting the length of a spacer 76 interposed between a flange 77 on the shaft 21 and a nut 78, which is secured above the transverse partition 15. The length of the rod 69 may also be adjusted in any conventional manner, as by means of a turnbuckle 79, so that when the desired penetration has been reached, the head 71 at the bottom of the rod 69 will move the arm 46 downwardly against the spring 45, thereby disengaging the latch 42 from the cam 43 on the block 39. When this occurs, the force exerted against the block 39 by the stiff spring 48 will apply a couple to the block 39, causing the drilling and sample receiving means 34 to rotate slightly about the end thereof, thereby breaking the sample away from the formation 75. When this occurs, the load on the motor 18 is suddenly reduced, so that the reading of the meter M at

the surface (Figure 1) drops, providing an indication that the sample has been broken off. The motor 18 is then deenergized by opening the switch S.

At this point, the housing 17 has dropped far enough in the chamber 14 to permit the spring detents 61 to slip over the head 59 of the retainer rod 57 adjacent the flats 60 thereon, as shown in Figure 3. By raising the cable 30 the rod 69 is moved upwardly so that the head 71 thereon engages the lug 70 and moves the block 39 to its initial position. This permits the spring 45 to move the latch 42 into engagement with the cam 43, thereby locking the block 39 in its initial position, as shown in Figures 2 and 6. Simultaneously, the shaft 21 pulls the flexible cable 32 upwardly, thus withdrawing the drilling and sample receiving means 34 from the formation 75 into the block 39. Also, the spring detents 61 lift the retainer rod 57 against the tension in the spring 67, causing the side wall gripping means 50 to pivot about the point 51 so as to move away from the side wall of the bore hole 74 and into the body of the side wall sample taker 19. When the cam 62 in the retainer rod 57 reaches the upper edge of the hub 58, the torsion spring 64 rotates the retainer rod 57 through approximately 90°, thereby bringing the key 62 substantially to the position shown in Figures 1 and 4, at which time the sample taker is completely reset and is ready to be moved to another location to take another sample, or to be raised to the surface of the earth.

On occasion, the motor 18 may come to rest with the cam 66 on the shaft 21 in a position tending to prevent rotation of the cam 65 on the retainer rod 57 to its normal locking position as shown in Figure 4. In order to insure proper operation under such conditions, the torsion spring 64 should be made strong enough to turn the shaft 21 against the load imposed by the reduction gearing 20 and the motor 18. If desired, sufficient angular lost motion may be provided between the cam 66 and the shaft 21 to insure return of the cam 65 to its locking position under all conditions of operation that might be encountered.

Since the length of the rod 69 may be adjusted to break off the sample after any predetermined depth of penetration of the drilling and sample receiving means 34 into a formation, the spacer 76 could be omitted.

If it is desired to take a plurality of samples on one trip into a bore hole, the lengths of the spacer 76 and the rod 69 should be adjusted so that the length of the sample cut during each sample taking operation is only a fraction of the total length of the drilling and sample receiving means 34. For example, if it is desired to take three cores, the lengths of the spacer 76 and the rod 69 should be such as to restrict the length of the cores cut by the apparatus to approximately one third the total length of the drilling and sample receiving means 34. In practice, it has been found that good results can be obtained with a drilling and sample receiving means about eight inches long. Three cores can be obtained with this apparatus in a single trip into a bore hole, although obviously, a single core the full length of the drilling and sample receiving means 34 may be obtained, if desired.

As indicated above, it is advantageous to maintain the pressure on the drilling and sample receiving means 34 close to an optimum value which may vary for different formations and conditions

of operation. A drilling and sample receiving means of $1\frac{1}{8}$ " inside diameter rotated at 700 R. P. M. under a pressure of 45 lbs. has been found entirely satisfactory, and requires about 1 $\frac{1}{2}$ minutes to cut a core 2 inches long in hard limestone.

The pressure applied to the drilling and sample receiving means 34 may be controlled by adjusting the weight of the motor 18 and the components secured thereto. If the weight of this equipment is not sufficient to produce the desired pressure, additional weight may be added to the motor 18 in any suitable manner. On the other hand if the weight of the equipment produces a higher pressure than is desired, the tension in the supporting cable can be controlled during the drilling operation to obtain the proper drilling pressure. Where this is done, a suitable cable tension indicator such as is described in prior Patent No. 2,353,249 to Maurice P. Lebourg should be employed.

From the foregoing, it will be apparent that the invention provides a new and improved side wall sample taker which is extremely simple and effective in operation. By mounting the electrical motive means slidably within the sample taker and applying the weight thereof to the drilling and sample receiving means during the sample taking operation, the operating pressure of the drill may be maintained constant regardless of its rate of penetration into a formation. Moreover, it will be understood that the novel side wall sample taker described herein can be readily dislodged and removed from the bore hole, even though failure of the power supply or of the electrical motive means occurs after the sample taking operation is under way.

Although reference has been made in the foregoing description to a suitably supported flexible shaft for transmitting pressure and rotation to the coring tool, it will be apparent that other equivalent means may be employed for this purpose. For example, a series of short rigid shafts coupled by universal joints could be used.

While a specific embodiment has been described above, the invention is not intended to be limited thereto, but is susceptible of numerous changes in form within the scope of the appended claims.

I claim:

1. In a side wall sample taker for use in a bore hole, the combination of a support carried by the sample taker and capable of limited movement within the sample taker at an angle to the longitudinal axis thereof, drilling and sample receiving means slidably mounted in said support and adapted for movement towards and away from the side wall of a bore hole, motive means mounted in said sample taker for causing said drilling and sample receiving means to advance from said support towards the side wall of a bore hole and to penetrate the same, means for holding said support and preventing movement thereof relative to the sample taker during a drilling operation, means for releasing said holding means to permit said support to be moved transversely of the direction of advancement of said drilling and sample receiving means and means carried by the sample taker and rendered effective upon the release of said holding means for imparting a sudden transverse movement to said support, to break off the sample from the formation.

2. In a side wall sample taker for use in a well, the combination of a support mounted for restricted movement in the sample taker and hav-

ing a bore therein, drilling and sample receiving means slidably mounted in said bore, motive means mounted in said sample taker for causing said drilling and sample receiving means to advance from said support and to penetrate the side wall of a well, means carried by the sample taker for urging said support substantially transversely of said drilling and sample receiving means, means carried by said sample taker retaining said support against transverse movement thereof relative to the sample taker, and means carried by said sample taker responsive to the penetration of said drilling and sample receiving means to a given depth in a formation for releasing said retaining means, whereby said urging means will cause a sudden transverse movement of said support, thereby breaking off from the formation a sample contained in the drilling and sample receiving means.

3. In a side wall sample taker for use in a well, the combination of a support mounted in said sample taker for restricted movement in a direction at an angle to the longitudinal axis of the sample taker and having a bore therein, drilling and sample receiving means slidably mounted in said bore for movement towards and away from the side wall of a well, motive means mounted in said sample taker for causing said drilling and sample receiving means to advance from said support towards the side wall of the well, spring means mounted on the sample taker and urging said support in said direction at an angle to the longitudinal axis thereof, means for retaining said support against movement with respect to the sample taker in said direction, and means responsive to the depth of penetration of said drilling and sample receiving means into a formation for releasing said retaining means, thereby permitting said spring means to move said support to break off from the formation a core contained in said drilling and sample receiving means.

4. In a side wall sample taker for use in a well, the combination of a support mounted for limited movement within the sample taker, drilling and sample receiving means slidably mounted in said support, motive means slidably mounted in the sample taker for up and down movement therein, operative connections for transmitting the rotational output and applying at least a portion of the weight of said motive means to said drilling and sample receiving means, means carried by the sample taker for holding said support and preventing movement thereof during a drilling operation, means for releasing said holding means, and means carried by the sample taker for automatically imparting a movement to said support, upon release of said holding means, to break off from a formation a sample contained in said drilling and sample receiving means.

5. In a side wall sample taker for use in a well, the combination of a support mounted for restricted movement in a direction at an angle to the longitudinal axis of the sample taker and having a bore therein, drilling and sample receiving means slidably mounted in said bore, motive means slidably mounted in the sample taker for up and down movement therein, a flexible driving connection between said motive means and said drilling and sample receiving means, guiding means carried by the sample taker for said flexible connection, said guiding means permitting transmission of the weight of said motive means to said drilling and sample

receiving means through said flexible connection, spring means carried by the sample taker urging said support in said direction at an angle to the longitudinal axis of the sample taker, means carried by the sample taker for retaining said support against movement in said direction, and means responsive to the depth of penetration of said drilling and sample receiving means into a formation for releasing said retaining means, thereby permitting said spring means to move said support to break off from the formation a core contained in said drilling and sample receiving means.

6. In apparatus for use in a bore hole, the combination of a body adapted to be lowered into a bore hole, a laterally movable side wall gripping member mounted in the body, means carried by the body for urging said wall gripping member into engagement with the side wall of a bore hole, means carried by the body for retaining said wall gripping member in inoperative position within the body, a member slidably mounted in the body for limited up and down movement therein, a supporting cable extending from said slidable member to the surface of the earth, means for releasing said retaining means to permit movement of said side wall gripping member into engagement with the wall of a bore hole, retracting means mounted in the body for restoring said wall gripping member to its inoperative position within the body, and means connected to said slidable member for linking said retracting means to said slidable member after a predetermined downward movement thereof, whereby said wall gripping member may be restored to the inoperative position by pulling on said cable to overcome the force exerted by said wall gripping member urging means.

7. In a side wall sample taker for use in a bore hole, the combination of a body adapted to be lowered into a bore hole, a laterally movable side wall gripping member mounted in the body, means for urging said wall gripping member outwardly from the body into engagement with the side wall of a bore hole, means for retaining said wall gripping member in inoperative position within the body, motive means slidably mounted in the body for limited up and down movement therein, a supporting cable extending from said motive means to the surface of the earth, drilling and sample receiving means slidably mounted in the body, operative connections for transmitting rotational movement and at least a portion of the weight of said motive means to said drilling and sample receiving means, means responsive to operation of said motive means for releasing said retaining means to permit movement of said side wall gripping member into engagement with the side wall of a bore hole, retracting means mounted in the body for restoring said wall gripping member to its inoperative position within the body, and means carried by said motive means and rendered effective after said drilling and sample receiving means has penetrated a predetermined distance into a formation for linking said retracting means to said motive means, to enable said side wall gripping member to be restored to, and retained in the inoperative position by pulling on said cable to overcome the force exerted by said wall gripping member urging means.

8. In a side wall sample taker for use in a bore hole, the combination of a support mounted for limited movement within the sample taker, drilling and sample receiving means slidably

mounted in said support, motive means slidably mounted in the sample taker for restricted up and down movement therein, a cable extending from said motive means to the surface of the earth, operative connections for transmitting the rotational output and applying at least a portion of the weight of said motive means to said drilling and sample receiving means; releasable means carried by the sample taker for holding said support and preventing movement thereof during a drilling operation, means movable with said motive means and responsive to the depth of penetration of said drilling and sample taking means into the side wall of a well for releasing said holding means, means for automatically applying a force to said support, upon release of said holding means, to cause said support to move so as to break off from a formation a sample contained in said drilling and sample receiving means, and actuator means carried by said releasing means for restoring said support to the position it occupied prior to the release of said holding means, said last named means being adapted to be actuated by raising said supporting cable.

9. A side wall sample taker for use in a bore hole, comprising a body adapted to be lowered into a bore hole and having side wall gripping means thereon, a laterally movable side wall gripping member mounted in the body, means for moving said wall gripping member outwardly from the body into engagement with the side wall of a bore hole, means for retaining said wall gripping member in inoperative position within the body, motive means slidably mounted in the body for limited longitudinal movement therein, a supporting cable extending from said motive means to the surface of the earth, drilling and sample receiving means slidably mounted in the body for movement towards and away from the side wall of a bore hole and mounted for limited lateral movement, operative connections for transmitting the rotational output and applying the weight of said motive means to said drilling and sample receiving means to cause the latter to penetrate the side wall of a well, means responsive to operation of said motive means for releasing said retaining means to permit movement of said side wall gripping member into engagement with the side wall of a bore hole, means carried by the body for restricting lateral movement of said drilling and sample receiving means during a drilling operation, means carried

by said motive means and responsive to a given penetration of said drilling and sample receiving means into a formation for releasing said movement restricting means, means carried by said sample taker for automatically applying a force to said drilling and sample taking means to cause lateral movement of said drilling and sample receiving means, upon release of said movement restricting means, to break off a sample contained therein from a formation, actuator means carried by said releasing means, and adapted to be actuated by raising said supporting cable for restoring said support to the position it occupied prior to the release of said movement restricting means, retracting means mounted in the body for restoring said wall gripping member to its inoperative position within the body, and means carried by said motive means for linking the latter to said retracting means when said motive means reaches a predetermined position, to enable said side wall gripping member to be restored to and retained in the inoperative position by pulling on said cable.

10. In a side wall sample taker for use in a bore hole, the combination of drilling and sample receiving means slidably mounted in the sample taker and adapted for movement towards and away from the side wall of a bore hole, means mounted in said sample taker for causing said drilling and sample receiving means to advance from the sample taker towards the side wall of a bore hole and to penetrate the same, means carried by said sample taker for applying a torque to said drilling and sample receiving means to break off a sample from a formation, means on said sample taker for restricting movement of said drilling and sample receiving means relative to said sample taker due to said torque applying means, and means for rendering said movement restricting means ineffective.
